(57) **CLAIM**

The ornamental design for a spool for dispensing waste disposal bags, as shown and described.

DESCRIPTION

FIG. 1 is a left isometric view showing my new design for a spool for dispensing waste disposal bags;

FIG. 2 is a right isometric view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof;

FIG. 8 is a right side elevation view thereof; and,

FIG. 9 is a left isometric view shown in an exemplary environment of use.

The broken lines are shown for the purpose of illustrating parts of the article as well as exemplary environmental subject matter. None of the broken lines form part of the claimed design. The spool for dispensing waste disposal bags is shown with a symbolic break in its length. The
